UNITED STATES PATENT OFFICE.

CHARLES K. GILES, OF CHICAGO, ILLINOIS.

WATCH-CASE.

SPECIFICATION forming part of Letters Patent No. 293,360, dated February 19, 1883.

Application filed September 13, 1883. (Model.)

To all whom it may concern:

Be it known that I, CHARLES K. GILES, a citizen of the United States, residing at Chicago, in the county of Cook and State of Illinois, have invented a certain new and useful Improvement in Watch-Cases, which is fully set forth in the following specification, reference being had to the accompanying drawings, in which—

10 Figure 1 represents a face view of a watch embodying my improvement; Fig. 2, a sectional view of the same, taken on the line xx' , Fig. 1, and on an enlarged scale; Fig. 3, an elevation of the central portion of the box 15 which receives the movement, on the same scale as Fig. 1; Fig. 4, a similar view of the back cap on the same scale; and Fig. 5 a similar view of the independent center on the same scale, and with a section broken away.

20 My invention relates to a watch in which the center, front, and back are separate and independent parts, and is an improvement upon the invention described in an application heretofore filed by me, June 13, 1883.

25 The present invention consists in various special features of construction, which I will proceed to describe in detail, and will then point out definitely in the claims the special improvements which I believe to be new and 30 wish to protect by Letters Patent.

In the drawings, A represents a band or ring, of suitable shape and size to receive the movement of the watch. At its upper edge it is provided with an external screw-thread section, a , and with an interior rabbet, a' , which serves as a seat for the front plate of the movement. At its lower edge it is provided with an external threaded section, a^2 , and a similar internal section, a^3 . The bezel B has a crystal, C, mounted therein in the usual way, and is provided with an internal screw-thread, b , whereby it is adapted to be turned on the upper edge of the band, the bezel being of such size and shape as to fit the band in this relation.

45 A back cap, D, is constructed to fit the inside of the band, and is provided with an external screw-threaded section, d , adapted to fit the internal threaded section, a^3 , at the lower edge of the band, as shown in Fig. 2 of the 50 drawings. When this cap is screwed into the band, it closes the back of the latter securely, but it does not project over the edge of the

band to provide a bearing for the center. A back plate, E, is constructed to fit the exterior of the band, and is provided with an interior threaded section, e , which is adapted to fit the external threaded section, a^2 , on the lower edge of the band. This back plate is preferably of the same size and of similar finish as the bezel, and both bezel and plate project outside of the band, as shown in Fig. 2 of the drawings. The center F is made in a separate and independent piece, and is adapted to fit the exterior of the band, and to fill the space between the projecting portions of the bezel and back 65 plate. It will be seen that, as the bezel is made removable from the band, the watch-movement can be placed in the latter at the front thereof, and so the band may be made somewhat smaller than when the bezel is in 70 one piece or is rigidly attached to the band, for then the movement must be introduced at the back, and of course the band must be large enough to receive the front plate and dial of the movement.

In the construction here shown and described only the front portion of the band extending as far as the seat need be made as large as the front plate of the movement. In my present improvement, as both the bezel and back plate 80 are screwed to the band, they may be drawn down tight on the center, so as to make perfectly tight joints, and at the same time hold the center in position, and by making the back cap of the band separate from the back plate 85 I am enabled to more fully protect the movement within the band. It will be understood, of course, that the bezel and back plate should be of the same material and such as is desired for the case, and of course the independent 90 center is also of the same material, unless it is desired to make a contrast between the parts of the case of the watch, which is practically made up of the three independent pieces—the bezel, back plate, and center.

95 In applying my present improvement to actual use, the watch-movement is placed within the band at the front thereof, either before or after the back cap is attached. The bezel is then screwed into the band, and the back cap screwed into the latter, if it has not been previously attached. The center is then slipped upon the band, adjusted in proper position, and the back plate screwed onto the band and

down upon the center, both back plate and bezel being turned hard upon the latter, to grip it closely and make tight joints.

The movement may be held from turning in 5 the band by an ordinary notch and pin, or any other suitable device, and when the bezel is screwed on the band it effectually fastens the movement in place, as it projects over the latter, as will be seen from the examination of 10 Fig. 2 in the drawings.

It is obvious that the band, bezel, and back cap, either with or without the back plate, may be used as a box for safely keeping and transporting the movement before the watch is set 15 up for use. It will be understood, of course, that the parts may be adapted either to stem-winding devices or ordinary key-winding devices.

The construction of the center as an inde- 20 pendent and removable piece enables me to make the design and ornament of this piece of varied styles, so that with the same bezel and back piece a center of different finish and design may be used; and, if desired, the center 25 may be changed at any time, and, in fact, the other parts may be changed also, for bezel, back, and center may be made in quantity and struck up of uniform fitting and size, but different design.

30 This improvement may also be adapted to embody my invention of an anti-magnetic shield for watches, for which I have heretofore made an application for Letters Patent, June 13, 1883.

35 If the band and cap are made of suitable material, it will only be necessary to apply the proper sheet of metal to the front plate or dial of the movement to entirely surround the latter with an anti-magnetic shield when the 40 watch is set up.

With the improvement which I have de- 45 scribed above I am enabled to make a cheap compact case for the watch when set up, and, at the same time secure the several advantages which have been mentioned above. I do not 50 wish to be understood, however, as limiting my improvement to the precise form and con-

struction of the parts described and as shown in the drawings, for it is obvious that changes may be made in this direction without chang- 50 ing the main idea of the improvement. It will also be seen that a portion of the improve- 55 ment may be obtained, even if the back cap should be made in one piece with the band, the bezel and back plate still remaining independent pieces screwed to the band, as de- 60 scribed. This construction, however, I do not consider so desirable as the one shown in the drawings and described above.

In the present application I wish it dis- 60 tinctly understood that I do not claim any- 65 thing shown in my prior applications filed May 31, 1883, and June 13, 1883, or the application filed of even date herewith, for an "improve- 70 ment in linings for watch-cases."

Having thus described my invention, what I claim as new, and desire to secure by Letters Patent, is—

1. A circular band adapted to receive a 70 watch-movement, and provided with a threaded section at each edge, in combination with a bezel provided with a screw-thread, a back plate also provided with screw-thread, and an independent "center" adapted to be placed 75 upon the band between the bezel and back plate, whereby both bezel and back plate are removably attached to the band by their threaded sections, and may be adjusted there- 80 on at pleasure to fix the position of the center and firmly clamp it between the two, sub- 85 stantially as and for the purposes set forth.

2. The circular band adapted to receive the 85 movement of a watch, and threaded, as de- 90 scribed, in combination with the screw- threaded bezel, the screw-threaded back cap, the screw-threaded back plate, and the in- 95 dependent center fitted to the exterior of the band, all constructed and operating substan- tially as and for the purposes set forth.

CHARLES K. GILES.
